UNITED STATES PATENT OFFICE.

NOAH EARLY, OF LAVINA, MONTANA.

GATE.

1,081,819.

Specification of Letters Patent.

Patented Dec. 16, 1913.

Application filed March 25, 1913. Serial No. 756,818.

To all whom it may concern:

Be it known that I, NOAH EARLY, a citizen of the United States, residing at Lavina, in the county of Musselshell and State of Montana, have invented a new and useful 5 Gate, of which the following is a specification.

The invention relates to improvements in gates.

10 The object of the present invention is to improve the construction of gates, and to provide a simple, practical and inexpensive gate of strong and durable construction, adapted to be easily and conveniently operated at a distance from either side of it without dismounting from a horse or leaving a vehicle.

A further object of the invention is to provide a gate of this character, which will 20 neither sag nor drag and which in opening will swing clear of snow and various other obstructions.

Another object of the invention is to provide a gate, equipped with latch mechanism 25 adapted to be automatically operated by the operating mechanism of the gate, and capable of effectually preventing stock from opening the latter.

With these and other objects in view, the 30 invention consists in the construction and novel combination of parts hereinafter fully described, illustrated in the accompanying drawings, and pointed out in the claims hereto appended; it being understood that 35 various changes in the form, proportion, size and minor details of construction, within the scope of the claims, may be resorted to without departing from the spirit or sacrificing any of the advantages of the invention.

In the drawings:—Figure 1 is a perspective view of a gate, constructed in accordance with this invention and shown closed. Fig. 2 is a vertical sectional view of the 45 same, the gate being midway between its open and closed positions. Fig. 3 is a central vertical sectional view, the gate being open. Fig. 4 is an enlarged vertical sectional view, illustrating the construction of 50 the latch. Fig. 5 is an enlarged side elevation of the same. Fig. 6 is a detail view, illustrating the means for connecting the inner ends of the operating levers.

Like numerals of reference designate corresponding parts in all the figures of the 55 drawings.

In the accompanying drawings in which is illustrated the preferred embodiment of the invention, 1 designates a double centrally pivoted counterbalanced gate, provided at its center with a vertical tube 2 suitably secured to the gate and projecting at the top to the bottom of the same. The lower portion of the tube receives a fixed vertical pivot 3, mounted in a sill 4 or other 60 suitable base and permitting the gate to move vertically and swing horizontally on it.

The gate, which may be of any preferred construction, may be either single or double, a double gate being preferable as it is perfectly counterbalanced and will, therefore, be easily operable whatever its size or weight.

The gate is provided at the bottom adjacent to the vertical central tube with a pair 75 of depending ears 4^a between which is pivoted one end of the link 5, which is pivoted or fulcrumed at its other end between a pair of upwardly extending perforated ears 6, located at the center of the swing of the 80 gate or midway between the positions occupied by the gate when the same is opened and closed.

When the gate is lifted by the means hereinafter described, the link will cause the 85 gate to swing and the momentum of the gate will carry the link beyond a vertical position and cause the gate to complete its opening and closing movement through gravity. This construction also enables the gate in 90 opening and closing to clear snow and other obstructions, so that it will not drag in such movements.

The gate is provided at its ends with upper and lower horizontal projecting portions 7, preferably consisting of outer terminals of the top and bottom bars of the gate, and adapted in the closing movement of the gate to drop into upper and lower brackets 8, mounted on vertical posts 9 and 100 adapted to rigidly support the gate in its closed position, so that when the gate is closed persons may climb over the same and cattle may rub or lean against it without unduly straining it or affecting its operation. 105 When the gate is opened, it rests upon blocks 10 and is received between uprights 11 and short posts or pieces 12 rising from the sill 4 and arranged in spaced relation with the uprights. By this construction, the gate 110 when opened is firmly seated and is braced against lateral movement.

The uprights 11, which are located at opposite sides of the gate when the latter is closed, are connected at their lower portions by the sill 4 and at their upper portions by a horizontal supporting bar or timber 13, suitably secured at its ends to the uprights at points below the upper ends thereof and also to the framework formed by the uprights, and the connecting members may be of any other preferred construction and may be braced in any suitable manner. The upper ends of the uprights are provided with slots or bifurcations 14 in which are pivoted operating levers 15, fulcrumed at an intermediate point between their ends on the said uprights and extending from points directly above the gate longitudinally of the roadway to points at suitable distances at each side of the gate, as clearly illustrated in Fig. 1 of the drawings. The outer ends of the operating levers are provided with short depending chains 16 of sufficient length adapted to be reached from the ground and also to be grasped by persons on horse back or in vehicles.

When a double gate is employed, horses and vehicles may approach the same so that the gate will always open away from the operator.

The upper end of the vertical tube receives a vertical latch operating rod 17, carrying a horizontal pin 18 operating in vertical slots 19 on the upper portion of the vertical tube 2, which extends through a metallic bearing 20 at the center of the supporting bar 13. The vertical tube slides and turns in the bearing of the supporting bar 13 and constitutes a vertical pivot or pintle for the gate. The slot and pin connection between the rod 17 and the upper portion of the vertical tube 2 permits a limited vertical independent movement of the rod to operate a latch 21. The latch 21, which is constructed of suitable metal, is pivoted at its lower portion by a pin or rivet 22 to an upwardly projecting arm or portion of a substantially L-shaped bracket 23. The bracket 23 may be of any preferred construction, and the pivot 22 is located above the lower edge of the latch, which is provided at the bottom with front and rear projecting portions 24 and 25, arranged to engage the supporting member to limit the pivotal movement of the latch to maintain the same in an upright position. The center of gravity of the latch is in advance of the pivot so that the latch is maintained by gravity in the engaging position illustrated in full lines in Figs. 1 and 5 of the drawings.

The upper end portion 26 is hook-shaped to engage a horizontal lug 27 of the vertical tube 2, and it is beveled at the front edge to enable the lug 27 in its downward movement to engage the hook-shaped upper portion of the latch and swing the latter rear-

wardly, whereby the lug of the tube is adapted to pass beneath the engaging portion of the latch. The latch is provided at the front with an intermediate projecting portion 28, presenting upper and lower inclined edges to the pin 18, which has one end extended to engage and trip the latch. When the gate is closed and the rod 17 is at the limit of its downward movement, the extended end of the horizontal pin 18 is arranged in the recess or space between the intermediate projecting portion 28 and the lower front projection 24 of the latch, and when the said rod 17 is lifted, its first movement, which is independent of the vertical tube 2, carries its pin 18 into engagement with the inclined edge of the intermediate projection 28 and swings the latch rearwardly from the position shown in full lines in Fig. 5 of the drawings to the dotted line position, thereby releasing the projecting lug 27 of the tube and enabling the latter and the gate to be lifted through a continued vertical movement of the rod 17. The upper inclined edge of the intermediate projection 28 enables the extended end of the pin to swing the latch rearwardly and pass beneath the said projection 28 in the closing movement of the gate, and the said pin 18 is also adapted after swinging the latch rearwardly to engage the front bottom projection and positively swing the latch into engagement with the projecting lug 27 of the vertical tube. When the hook-shaped top portion of the latch is in engagement with the lug 27, the gate is securely held against the vertical movement, which is necessary to open it, and it will be impossible to open the gate by upward pressure on the same, so that it cannot be operated by stock. The lug 27 extends horizontally from the upper end of the vertical tube 2 at one side thereof, and the tube is provided at the opposite side with a lug or projection 29 to which is connected the lower end of a coiled spring 30, secured at its upper end to a horizontally projecting arm 31 of the rod 17 and adapted to maintain the rod 17 at the limit of its downward movement to insure a proper latching of the gate and to prevent the latch from being accidentally tripped. The latch is arranged above the gate out of the way and is preferably housed within a suitable casing 32, mounted upon the supporting bar 13 and receiving the upper portion of the tube 2 and the rod 17, and provided at the top with a central opening through which passes a connecting screw 33. The connecting screw 33 is provided at its lower end with a hook or eye 34, which engages a perforation in the upper end of the rod 17, and the upper portion of the screw is threaded and extends through a connecting plate or piece 35, secured to the inner end of one of the levers 15 and form-

ing an extension of the same and passing through an eye 36, which depends from the adjacent operating lever. The outer terminal portion 37 of the connecting plate or piece is hook-shaped to maintain itself in engagement with the eye 36, and the terminal portion of the connecting plate or piece, and the eye 36 form a loose hinge connection between the levers and permit the necessary play of the inner ends thereof in the oscillation of the same. The upper end of the screw receives a nut 38 by means of which the connection between the levers and the rod 17 is adjusted. When the outer arm or portion of either of the operating levers is swung downwardly, the latch is tripped and the gate is lifted and swung on its pivot, and the momentum of the gate will carry the link beyond a vertical position and cause the gate to automatically complete its swinging movement.

What is claimed is:—

1. The combination of a gate, means for mounting the same to permit the gate to have a limited vertical sliding movement and a horizontal pivotal or swinging movement, a latch located above the gate and arranged to lock the gate in its closed position, and operating mechanism connected with the gate and having means for tripping the latch.

2. The combination of a gate, means for mounting the same to permit the gate to have a limited vertical sliding movement and a horizontal pivotal or swinging movement, means connected with the gate for causing the same when lifted to swing horizontally, a latch located above the gate and arranged to lock the same against vertical movement, and operating mechanism connected with the gate and adapted to lift the same and provided with means for tripping the latch.

3. The combination of a gate, means for mounting the same to permit a horizontal pivotal or swinging movement and a vertical sliding movement, a latch located above the gate and arranged to lock the same against vertical movement, and operating mechanism including a member connected with the gate and having a limited movement independently of the same and provided with means for tripping the latch to release the gate.

4. The combination of a gate, means for mounting the same to permit a horizontal pivotal or swinging movement and a vertical sliding movement, a pivotally mounted latch located above the gate and arranged to lock the same against vertical movement and having spaced portions, and operating mechanism including a member connected with the gate and having a limited movement independently of the same and provided with means arranged to operate be-

tween the spaced portions of the latch for tripping the latter and for positively moving the latch to its engaging position.

5. The combination of a gate, means for mounting the same to permit a horizontal pivotal or swinging movement and a vertical sliding movement, a pivoted latch having a substantially hook-shaped engaging top portion for holding the gate against vertical movement and provided below the same with a projecting portion having upper and lower inclined edges, and operating mechanism including a vertically movable member connected with the gate and having a limited movement independently thereof and provided with means arranged to engage with the said inclined edges of the latch and adapted to trip the said latch.

6. The combination of a gate mounted for horizontal swinging movement and a limited vertical movement and provided with a projecting lug, a pivoted latch located above the gate and arranged to engage the said lug, operating mechanism including a vertically movable member connected with the gate and having a limited movement independently thereof and provided with means for engaging and tripping the latch.

7. The combination of a gate, means for mounting the same to permit the gate to move vertically and swing horizontally, a relatively fixed lug carried by the gate, a latch located above the gate and provided at the top with means for engaging the said lug, said latch being also provided with spaced portions located below the engaging means, and operating mechanism including a vertical rod connected with the gate and having a limited independent movement and provided with means arranged to engage with the said spaced portions to trip the latch and also to reengage the same with the lug.

8. The combination of a gate, means for mounting the same to permit the gate to move vertically and swing horizontally, a pivoted latch having an engaging portion for holding the gate against vertical movement and pivoted at its lower portion, said latch being provided at the bottom with means for limiting its pivotal movement to maintain it in an upright position, and operating mechanism including a substantially vertical rod connected with the gate and having an independent upward and downward movement and provided with means for tripping the latch.

9. The combination of a gate having a vertical tube extending above the gate, means for moving the tube to permit the gate to move vertically and swing horizontally, a latch arranged to engage the tube for locking the gate against vertical movement, and operating mechanism provided with a rod extending into and connected

- 4
- with the tube and having a limited independent movement, said rod being provided with means for tripping the latch.
10. The combination of a gate provided 5 with a vertical tube extending above the gate and having a slot, means for mounting the tube to permit the gate to have a vertical sliding movement and a horizontal pivotal movement, a rod extending into the 10 tube and provided with a pin operating in the said slot and projecting beyond the tube, a latch arranged to engage the tube for holding the gate against vertical movement, said latch being located in the path of the 15 projecting pin and adapted to be tripped by the same, and means connected with the rod for lifting the gate.
11. The combination of a gate, means for mounting the gate to permit the same to 20 swing horizontally and move vertically, a pivoted latch arranged to lock the gate against vertical movement, operating mechanism including a member connected with the gate and having a limited movement in- 25 dependently of the same and provided with means for tripping the latch, and a coiled spring connected with the gate and with the said member for maintaining the same normally at the limit of its movement in one 30 direction.
12. The combination of a gate provided with a vertical tube, means for mounting the tube to permit the gate to swing horizontally and slide vertically, a latch ar- 35 ranged to engage the tube for holding the gate against vertical movement, a rod con- nected with and slidably freely in the tube
- and having means for tripping the latch, operating levers extending to points above the tube, adjustable means for connecting 40 the inner ends of the operating levers with the said rod, and a coiled spring connecting the rod and the tube for maintaining the rod at the limit of its downward movement.
13. The combination of a fixed vertical 45 pivot, a gate provided with a tube having its lower portion fitted over the said pivot, said gate being adapted to move vertically and swing horizontally, a latch arranged to engage the tube for holding the gate 50 against vertical movement, and operating means including a member slidable in the upper portion of the tube and having means for engaging and tripping the latch.
14. The combination of a fixed vertical 55 pivot, a gate provided with a vertical tube having its lower portion fitted over the said pivot and permitting the gate to swing horizontally and move vertically, a supporting framework provided with a bearing slidably 60 receiving the upper portion of the tube, a latch mounted on the framework and ar- ranged to engage the tube for locking the gate in its closed position, and operating mechanism mounted on the said framework 65 and including a member guided by the tube and having means for tripping the latch.

In testimony, that I claim the foregoing as my own, I have hereto affixed my signature in the presence of two witnesses.

NOAH EARLY.
